AIR COMPRESSING UNIT

Harold R. Gamble, Toledo, Ohio, assignor to The De Vilbiss Company, Toledo, Ohio, a corporation of Ohio

Application September 29, 1954, Serial No. 32,479

Term of patent 14 years

(Cl. D65—1)

To all whom it may concern:

Be it known that I, Harold R. Gamble, a citizen of the United States, residing at Toledo, county of Lucas, State of Ohio, have invented a new, original, and ornamental Design for an Air Compressing Unit, of which the following is a specification, reference being had to the accompanying drawing, forming part thereof.

In the drawing:

Fig. 1 is a side elevational view of an air compressing unit showing my new design;

Fig. 2 is a front end thereof; and

Fig. 3 is a rear end view thereof.

I claim:

The ornamental design for an air compressing unit, as shown.
